Stuart W. Parsons
ATTORNEY.

UNITED STATES PATENT OFFICE.

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT.

DOOR-HOLDER.

1,151,122.

Specification of Letters Patent. Patented Aug. 24, 1915.

Application filed March 2, 1914. Serial No. 821,870.

To all whom it may concern:

Be it known that I, STUART W. PARSONS, a citizen of the United States, and a resident of New Britain, in the county of Hartford and State of Connecticut, have invented certain new and useful Improvements in Door-Holders, of which the following is a specification.

This invention relates particularly to a device adapted to hold a door in open position. It was originally intended for application to garage or barn doors, though it may be adapted for other uses.

In the drawings, Figure 1 is a sectional top view showing the position which the parts of the device assume when the door is closed, the top of the door frame being removed. Fig. 2 is a view similar to Fig. 1 but with the door open, and the top of the door frame being shown. Fig. 3 is a detail side view of the joint between the two members of the holder. Fig. 4 is a view looking from the underside of Fig. 3.

Referring to the drawings, *a* denotes a portion of the wall of the building, *b* the frame, and *c* the top thereof, and *d* the door supported on suitable hinges *e*. The holder comprises a pair of attachment members 1, 2, one of which, as 1, is secured to the underside of the top member of the door frame, and the other, 2, to the inner face of the door near its upper edge, and a pair of arms 3, 4, pivotally connected with the attachment members 1, 2, respectively, and with their inner ends connected together with the slip connection formed by a pin 5 on the arm 3 which works in a slot 6 in the arm 4. When the arms 3, 4, are in extended position as shown in Figs. 2, 3 and 4, the curved end 7 of the arm 3 acts against a stop 8 on the arm 4 to prevent the relative longitudinal movement of the arms, and the two arms are held in extended position by the friction catch 9 constituted by a projection on the underside of the arm 4 which enters a depression in the arm 3.

10 is a chain attached to one of the arms, as 4, near the point of its connection with the other arm, and carried laterally over 50 to an eye 11 which may be conveniently secured to the door and provides a means for

breaking the joint to admit of the closing of the door.

The arms 3, 4, are formed from angle iron in order to provide a proper stiffness and 55 rigidity for the structure, and as will be seen by reference to Fig. 1, when the door is closed the arm 3 fits under the arm 4 and assists in its support, the adjacent lateral webs of the angle iron arms being in contact 60 with each other. It will also be observed that the attachment members are secured to the door frame and door at a sufficient distance from that side of the frame upon which the door is hinged to enable the arms to 65 close together very compactly within the door frame; at the same time, the device when extended will hold the door in full open position and is up out of the way of the tops of carriages, automobiles, etc., which 70 may be passing through the door. The attachment member 2 is preferably in the form of a channel iron, which affords a support for the arm 4 when the device is closed, and somewhat relieves the strain on the pivotal 75 connection of the two parts.

The structure as here illustrated and described is susceptible of alterations and modifications without departing from the spirit of the invention.

I claim as my invention:—

1. In a device of the character described, the combination with a door frame and a door hinged at one side thereof, of a holder comprising a pair of attachment members, 85 one of which is secured to the underside of the top of said door frame and the other near the top of said door, and at suitable distances from the hinge support of said door, and a pair of arms pivotally connected 90 with said members at their outer ends, a slot and pin pivotal connection between the inner ends of said arms, a stop on one of said arms adapted for coöperation with the laterally curved inner end of the other arm 95 and a frictional catch between the inner ends of the said arms.

2. In a device of the character described, the combination with a door frame and a swinging door carried at one side thereof 100 on hinged supports, of a pair of attachment members, one of which is secured to the un-

derside of the top of said door frame and the other near the top of said door, and a suitable distance from said hinged support, and a pair of arms having lateral webs, said

5 arms being pivotally connected at their outer ends to said supports and provided with a shifting pivotal connection for their

inner ends, said arms being adapted to fold together when the door is closed, with one of said lateral webs underlying the other.

STUART W. PARSONS.
